(57) CLAIM

We claim the ornamental design for a football helmet, as shown and described.

DESCRIPTION

FIG. 1 is a perspective view of a first embodiment of a football helmet;

FIG. 2 is a front view of the helmet of FIG. 1;

FIG. 3 is a side view of the helmet of FIG. 1, the opposite side being a mirror image; and

FIG. 4 is a top view of the helmet of FIG. 1.

FIG. 5 is a perspective view of a second embodiment of a football helmet;

FIG. 6 is a front view of the helmet of FIG. 5;

FIG. 7 is a side view of the helmet of FIG. 5, the opposite side being a mirror image; and,

FIG. 8 is a top view of the helmet of FIG. 5.

Those portions of the present invention which are presented in broken or dotted lines show the environment of the design only and form no part of the claimed design. Moreover, any shading presented in the accompanying drawings is provided merely to highlight the contour of the invention and is not intended to be illustrative of texture or gloss.
